UNITED STATES PATENT OFFICE.

JOSEPH FENNER, OF BROCKTON, MASSACHUSETTS.

DESIGN FOR AN INNER SOLE.

SPECIFICATION forming part of Design No. 33,162, dated September 4, 1900.

Application filed July 19, 1900. Serial No. 24,224. Term of patent 14 years.

To all whom it may concern:

Be it known that I, JOSEPH FENNER, a citizen of the United States, residing at Brockton, in the county of Plymouth and State of Massachusetts, have invented and produced a new and original Design for Inner Soles, of which the following is a specification, reference being had to the accompanying drawings, forming part thereof.

10 Figure 1 is a plan view of an inner sole, showing my new design. Fig. 2 is an edge view or front elevation. Fig. 3 is a sectional view taken on the line 3 3 of Fig. 1.

As shown in the drawings, the leading or 15 material feature of my design consists of a comparatively-thick inner part or body portion bounded by an inclined groove or sloping face, and at the lower extremity of said sloping face or groove is a projecting lip or 20 rib portion, the latter being substantially L-shaped in cross-section and consisting of a comparatively-thin upright part and a thicker lower part terminating in a stub edge, said lip or rib portion extending around the greater 25 part of the inner sole slightly in front of the edge thereof, said inner sole having outside of said

loop a thin feather-edge whose upper portion is substantially level with the bottom groove. The comparatively-thick portion a^1 is bounded by a groove or sloping face a^1 , terminating at a^2 adjacent to a thin outer part a^3 , thick lower part a^4 , terminating in edge a^5 , and beyond said rib is a feather-edge a^6 , whose upper surface a^7 is substantially level with the lower part a^2 of a^1 .

The surface of the inner sole a^1 has thin portions of the projecting lip a^2 with a canvas-like surface, as clearly shown in Fig. 1 and indicated in Fig. 3.

Having fully described my invention, I claim as new, and desire to secure a Patent, is—

The design for an inner sole hereinafter described.

In testimony whereof I have signed my name to this specification in the presence of two subscribing witnesses.

JOSEPH FENNER
